[57] ABSTRACT

One or more gaseous discharge lamps which have a negative resistance characteristic are connected to a ballast circuit which includes a transformer having primary and secondary coils and a core having a portion of reduced cross-sectional area. The core also includes a high-reluctance shunt which is arranged to cooperate with the portion of reduced cross-sectional area to provide a path for a portion of the magnetic flux linking the windings of the primary coil that does not link the windings of the secondary coil. This construction diminishes the tendency of the current flow in the secondary coil to increase as the resistance of the lamp decreases. In addition, it improves voltage regulation and the crest factor of the current.

ILLUMINATING APPARATUS AND BALLAST CIRCUIT

BACKGROUND OF THE INVENTION

This invention relates to illuminating apparatus of the gaseous discharge type, and more particularly to illuminating apparatus of the gaseous discharge type in which the lamps have a negative resistance characteristic that requires the use of a ballast circuit.

It is well known that gaseous discharge lamps generally have a negative resistance characteristic. By this it is meant that as the current flow through the lamp increases the resistance of the lamp decreases. Thus, these lamps present a relatively high resistance when they are first turned on and a relatively high voltage must, therefore, be applied to start the lamps. However, after the current begins to flow between the filaments of the lamp, the resistance falls off and the current continues to increase. If the appropriate circuit elements are not included in combination with the lamp to provide an impedance to the flow of current, the current will increase until the lamp reaches what is known as a "runaway condition" and burns out. Accordingly, it is conventional to employ a ballast circuit which provides this needed impedance in combination with such lamps.

Conventional ballast circuits usually include a capacitor arranged in series with the lamp to provide the required impedance. Conventional ballast circuits also include a transformer to provide the voltage necessary to start and operate the lamp from an available alternating-current power supply. The total impedance presented by the ballast circuit is, of course, a combination of the inductive reactance of the transformer and the capacitive reactance of the capacitor. Ballast circuits of this type are sometimes combined with two gaseous discharge lamps which are arranged for sequence starting and series operating.

In addition to the capacitor mentioned above which is connected in series with both lamps across the secondary coil of the transformer, a starting capacitor is often connected in parallel with one of the two lamps. When power is first supplied to the transformer, the starting capacitor provides a path by which the current bypasses one of the two lamps and the available voltage is impressed upon the other lamp which is started first. After this lamp has started and its resistance drops, the voltage drop across the unstarted lamp becomes high enough to start it, and its resistance drops to the extent that the current flow through the starting capacitor is insubstantial.

Because the brightness of gaseous discharge lamps is dependent, to a considerable extent, upon the voltage supplied across their filaments, it is highly desirable if voltage regulation can be built into the ballast circuit. The effect of the apparatus upon the power factor is another important consideration in designing a ballast circuit. The crest factor of the current which flows through the lamps is an additional operating parameter to be considered when evaluating the performance of a ballast circuit, primarily because of its effect on the operating life of a lamp.

It has previously been proposed by this inventor that conventional ballast circuits could be improved by forming a slot or hole in the center portion of the transformer core surrounded by the secondary coil. This

modification of the transformer brings about a desirable saturation of the portion of the core which has a reduced cross-sectional area and thereby improves the operation of the ballast circuit. This earlier invention is explained in detail in Pat. No. 4972 issued by the Republic of the Philippines on May 11, 1970.

To fully appreciate the problems involved in the design of ballast circuits it must be understood that they are utilized in connection with lamps, such as conventional fluorescent lamps used in homes and offices, which must be designed for high production at a minimum cost. It therefore follows that small sophisticated improvements in their design which enable them to be produced at a lower cost utilizing less expensive components are of great significance

SUMMARY OF THE INVENTION

This invention consists of an important improvement in the design of ballast circuits employing the board principle of reducing the cross-sectional area of a portion of the transformer core. A transformer is employed which has a primary coil adapted to be connected to an alternating-current power supply, a secondary coil adapted to be connected to one or more gaseous discharge lamps, and a core with which the primary and secondary coils are magnetically associated. A high-reluctance shunt is arranged to cooperate with the portion of the core which is of reduced cross-sectional area and is positioned to provide a path for a portion of the magnetic flux linking the windings of at least a part of the primary coil that does not link the windings of a substantial part of the secondary coil. This construction reduces the tendency of the current flow in the secondary coil to increase as the resistance of the lamp decreases. It also improves the voltage regulation inherent in the ballast circuit.

Preferably, the portion of the transformer core which is of reduced cross-sectional area is disposed adjacent to one end of the secondary coil. It is formed by at least one indentation in the centerpiece of the core. The high-reluctance shunt is formed by a protruding portion attached to a side structure of the core which projects part way into the indentation.

In a preferred embodiment of the invention, the transformer core is of the shell type in which the two opposite ends of the centerpiece about which the primary and secondary coils are wound are connected by a side structure. In this embodiment, the portion of the core of reduced cross-sectional area is formed by two indentations oppositely disposed on the sides of the centerpiece and the shunt is formed by two protruding portions on the side structure, one of which projects part way into each of the two indentations.

The entire core is made of a plurality of laminations arranged to form a stack. This is a conventional arrangement which is desirable because it minimizes eddy current losses. An important feature of this transformer is that, because the protruding portions of the side structure coincide with the indentations in the centerpiece, the laminations of the centerpiece and the side structure can conveniently be made by one punching operation which produces a minimum of scrap.

The ballast circuit of this invention can be combined with first and second gaseous discharge lamps each

having a negative resistance characteristic. An operating capacitor is connected in series with the secondary coil and the first and second lamps to provide an impedance whereby the tendency of the current to increase as the resistance of lamps decreases is further diminished. A starting capacitor is connected in series with the first lamp and the secondary coil and in parallel with the second lamp whereby, when the apparatus is first connected to the power supply, the current passes through the starting capacitor and bypasses the second lamp until the first lamp is started. The second lamp is then started after the resistance of the first lamp has diminished.

The entire ballast circuit may be encapsulated in a block of material and a temperature sensing means for disconnecting the primary coil of the transformer from the power supply when the temperature rises above a predetermined level may be included. This will protect the device and the surrounding environment in the event that excessive heat is created due to a malfunction of the apparatus.

The ballast circuit described above has been found to be particularly suitable for use in combination with fluorescent lamps. Its voltage regulating effect, its crest factor, and its effect on the power factor have been found to be quite desirable in comparison to previously known ballast circuit constructions. Moreover, when the transformer of this invention is employed it is possible to utilize a smaller operating capacitor than would otherwise be required to provide the necessary impedance and to prevent a runaway condition of the lamps from being reached. The functionally desirable shape of the laminations of the centerpiece and side structure of the transformer coil facilitates the manufacture of these sheets of material by a single punching operation which produces a minimum of scrap.

BRIEF DESCRIPTION OF THE DRAWINGS

For a more complete understanding of the invention, reference may be made to the following detailed description taken in conjunction with the accompanying figures of the drawings in which:

FIG. 1 is a partially schematic cross-sectional view of a transformer suitable for use in a first embodiment of the invention;

FIG. 2 is a cross-sectional view taken along the line 2—2 of the transformer of FIG. 1;

FIG. 3 is a schematic view of an illuminating apparatus including a ballast circuit constructed in accordance with the invention and employing the transformer of FIG. 1;

FIG. 4 is a partially schematic cross-sectional view of a transformer suitable for use in a second embodiment of the invention;

FIG. 5 is a schematic diagram of an illuminating apparatus including a ballast circuit constructed in accordance with the invention and employing the transformer of FIG. 4; and

FIG. 6 is a graph showing a typical wave form of the current that flows through the lamps of the circuit shown in FIGS. 3 and 5.

DESCRIPTION OF THE PREFERRED EMBODIMENT

FIG. 1 shows a partially schematic cross-sectional view of an isolation transformer 10 suitable for use in a ballast circuit constructed in accordance with the invention. The transformer 10 includes a core 12 formed by a centerpiece 14 and a side structure 16. The side structure 16 is made of a pair of symmetrical side pieces 18 and 20 which connect the ends of the centerpiece 14. As can best be seen in the cross-sectional view of FIG. 2, each portion of the core 12 is made up of a plurality of laminations 22 punched from a sheet of magnetic material and arranged to form a stack.

The transformer 10 is an isolation transformer which includes a primary winding 24 and a separate secondary winding 26. The centerpiece 14 of the transformer core 12 includes a portion 28 which is of reduced cross-sectional area. The portion 28 is located between two indentations 30 which are disposed on opposite sides of the centerpiece 14. The side structure 16 of the core 12 carries a pair of protruding portions 32 one of which projects part way into each of the indentations 30. The protruding portions 32 are dimensioned so as to leave a non-magnetic gap between the protruding portions 32 and the centerpiece 14. The protruding portions 32 cooperate with the indentations 30 to form a pair of high-reluctance shunts 34 disposed between the primary coil 24 and the secondary coil 26.

The transformer 10 includes a pair of leads 36 by which the primary coil 24 is adapted to be connected to an alternating-current power supply. A pair of leads 38 are provided for connecting the secondary coil 26 to a lamp. A plurality of leads 40 are provided for connecting a pair of auxiliary secondary coils 42 (not shown in FIG. 1) to the filaments of a gaseous discharge lamp of the continuously heated filament type.

FIG. 3 shows a schematic diagram of the transformer 10 of FIG. 1 arranged in combination with a gaseous discharge lamp 44 which may be of the fluorescent type having a negative resistance characteristic. The lamp 44 is connected by the leads 38 to the secondary coil 26. It is connected in series with an operating capacitor 46. The lamp 44 includes a pair of continuously heated filaments 48 each of which is connected to one of the auxiliary secondary coils 42 by the leads 40.

The high-reluctance shunts 34 provide paths for part of the flux generated by the primary coil 24 which does not link the windings of the secondary coil 26. Although this flux is intentionally permitted to avoid the secondary coil 26, it may be referred to as leakage flux. As the current increase and the magnetic flux in the core 12 of the transformer 10 increases, the portion 28 of the centerpiece 14 which is of reduced cross-sectional area will tend to become saturated. As the saturation of the portion 28 increases the amount of leakage flux following the path which does not link the windings of the secondary coil 26 will increase. This tends to limit the current induced in the secondary coil 26.

It will be recalled that the lamp 44 has a negative resistance characteristic, and, therefore, once started it will tend to draw a larger and larger current until it reaches a runaway condition if an impedance is not provided to limit the current supplied to the lamp 44. The operating capacitor 46 provides part of this needed

impedance. However, because of the current limiting effect of the high-reluctance shunts 34 on the secondary coil 26, the capacitor 46 may have a substantially smaller farad capacity than would be necessary if the shunts 34 were not provided and the centerpiece 14 of the transformer core 12 were of constant cross-sectional area. Thus, the tendency of the current flow in the secondary coil 26 to increase as the resistance of the lamp 44 decreases is diminished by the shunts 34. Accordingly, the apparatus shown in FIG. 3 can be manufactured at a lower cost because of the reduction in the size of the capacitor 46.

It should be noted that the presence of the high-reluctance shunts 34 also provides for improved voltage regulation in the transformer 10. A variation in the voltage applied across the leads 36 of the primary coil 24 will produce a proportionately smaller variation in the voltage induced in the secondary coil 26, partly because of the construction of the core 12 and the shunts 34.

Another advantage of the transformer construction described above is that the crest factor of the current that flows through lamp 44 is minimized and may be made substantially lower than the crest factors associated with previously known transformers for use in ballast circuits. The crest factor is defined as the ratio of the maximum current flow which occurs during a cycle of the alternating-current passing through the lamp 44 to the root-mean-square value of that current. Hence, a current which flows in the form of a relatively flat wave will have a low crest factor as compared to a current which flows as a wave that rises sharply in the form of a spike. It has been found that current having a low crest factor contributes to long life and stable operation of gaseous discharge lamps. A graphical representation of an oscilloscope tracing produced by the current flowing through the circuit of FIG. 3 is depicted in FIG. 6. The precise shape of the wave form is, of course, dependent upon the particular circuit components selected and this graph is merely illustrative of a typical wave form. The ordinate of the graph of FIG. 6 represents current amplitude and the abscissa represents time. No scale of numerical values is given in conjunction with this graph because only the shape of the wave is of interest here.

Consistent with the objective of minimizing the manufacturing cost of the apparatus, the laminations 22 of which the core 12 is made are shaped so that they conveniently fit together and do not overlap. For this reason, the side members 18 and 20 and the centerpiece 14 can be punched together from a single sheet of magnetic material thereby affecting a considerable savings.

It is desirable to enclose all of the components of the ballast circuit shown in FIG. 3 in a block of encapsulating material. A section of such an insulating block 85 is represented diagrammatically in broken lines in FIG. 3. A temperature responsive means 50 for disconnecting the primary coil 24 from the power supply in the event of a rise in the temperature of the block of material above a predetermined level due to a malfunction of the apparatus can be included in the circuit.

A second embodiment of the invention is shown in FIGS. 4 and 5. FIG. 4 shows a partially schematic cross-sectional view of a transformer 52 having a core 54.

This core 54 is of the same design as the core 12 shown in FIG. 1. The parts of the core 54 are, therefore, designated by the same numbers as the corresponding parts of the core 12 of the transformer 10 and are not separately described here.

The transformer 52 differs from the transformer 10 in that it is an autotransformer instead of an isolation transformer. Thus, there is, in effect, only one transformer coil 56 which is divided into two parts 58 and 60. A pair of high-reluctance shunts 61 formed by the projecting portions 32 and the indentations 30 of the transformer core 54 separate these two sections 58 and 60 of the coil 56. The entire coil 56 functions as the secondary coil of the transformer 52. The section 58 of the coil 56 also functions as the primary coil of the transformer 52.

FIG. 5 is a schematic circuit diagram of the transformer 52 arranged in combination with a first lamp 62 and a second lamp 64. Each of the lamps 62 and 64 are of the gaseous discharge type and have a negative resistance characteristic. They may be conventional fluorescent lamps. The primary coil 58 is adapted for connection to an alternating-current power supply by a pair of leads 66. An operating capacitor 68, which is connected in parallel with a leakage resistor 70, is connected in series with the first lamp 62, the second lamp 64, and the secondary coil 56. A starting capacitor 72 is connected in series with the first lamp 62 and the secondary coil 56 and in parallel with the second lamp 64.

The operating capacitor 68 performs the same function as the operating capacitor 46 shown in FIG. 3. It provides an impedance in series with the lamps 62 and 64 to prevent them from reaching a runaway condition as their resistance decreases. The function of the starting capacitor 72 is to allow the current to bypass the second lamp 64 when the primary coil 58 is first connected to the power supply. Because the current flows through the starting capacitor 72 instead of the second lamp 64, the voltage applied across the first lamp 62 is higher than it would be if the current from the secondary coil 56 passed through the two lamps 62 and 64 in series. Thus, a relatively high starting voltage is applied to the first lamp 62 and, after the lamp 62 has started and its resistance has decreased, the voltage drop across the starting capacitor 72 begins to rise until the second lamp 64, which is connected in parallel with the starting capacitor 72, is also started. When both lamps 62 and 64 are in a stable operating condition, the current passing through the capacitor 72 is insubstantial. Thus, because the operating capacitor 68 and the starting capacitor 72 are employed in combination, the lamps 62 and 64 are started sequentially but are operated in series.

The lamps 62 and 64 are both of the continuously heated filament type. Accordingly, these lamps each include a pair of filaments 74 that are continuously supplied with current from a plurality of auxiliary secondary coils 76. The auxiliary coils 76 are connected to the filaments 74 by a plurality of leads 78. The second coil 56 is connected to the lamps 62 and 64 by a pair of leads 80. A temperature responsive means 82 for disconnecting the primary coil 58 from the power supply in the event of a rise in the temperature above a predetermined level is provided as in the apparatus of FIG. 3.

As in the embodiment shown in FIG. 3, the protruding portions 32 of the transformer core side structure 16 cooperate with the indentations 30 to form a pair of high-reluctance shunts which are designated 61 in FIGS. 4 and 5. These high-reluctance shunts 61 provide a path for the magnetic flux linking the windings of the primary coil 58 that does not link the windings of a substantial part 60 of the secondary coil 56 whereby the tendency of the current flow in the secondary coil 56 to increase as the resistance of the lamps 62 and 64 decreases is diminished. Moreover, as explained in reference to the embodiment of FIG. 3, the presence of the high reluctance shunts 61 in combination with the portion 28 of the core 54 which is of reduced cross-sectional area improves the voltage regulation which is inherent in the construction of the transformer 52. Another inherent advantage to this construction is that the crest feature of the wave is of a lower value than can be obtained utilizing previously known concepts of transformer design.

It will be clear from the above description that the invention embodied in the apparatus of FIGS. 3 and 5 represents an advance of considerable significance in the art of illumination by gaseous discharge lamps. Because the design of the apparatus minimizes manufacturing costs it is particularly suitable for use in conjunction with fluorescent lamps which are associated with high volume production and, therefore, place great emphasis on the minimization of the cost of ballast circuit components.

It will be obvious to those skilled in the art that the above-described embodiments are meant to be merely exemplary and that they are susceptible of modification and variation without departing from the spirit and scope of the invention. Therefore, the invention is not deemed to be limited except as defined by the appended claims.

I claim:

1. A ballast transformer for use in a ballast circuit for starting and operating a gaseous discharge lamp having a negative resistance characteristic; the transformer comprising a primary coil and a secondary coil, a core defining a magnetic circuit linking the primary and secondary coils, the core including a centerpiece encircled by the coils and at least one said member which completes a magnetic circuit linking the primary and secondary coils through the centerpiece and through the side member from one end of the centerpiece to another end of the centerpiece, and means for preventing an extreme increase in flux linking the substantial secondary section upon starting of a gaseous lamp connected thereto, said means for preventing including a saturable narrowed section of the centerpiece intermediate the primary coil and at least a substantial section of the secondary coil, and a high-reluctance shunt near said narrowed section located to divert flux from the saturated narrowed section and through the shunt and forming a leakage magnetic path from the centerpiece to the side member that does not link said substantial secondary section, the magnetic circuit through the centerpiece and through the side member being, absent saturation, of lower reluctance than the leakage magnetic path through the centerpiece, the shunt, and the side member, whereby a greater portion of flux is diverted through the high-reluctance shunt after starting of a gaseous discharge lamp connected with said

secondary coil causing saturation in the narrowed section of the centerpiece.

2. The ballast transformer of claim 1, said narrowed section of the centerpiece being formed by at least one indentation in said centerpiece and said shunt being formed by at least one protruding portion attached to said side member which projects part way into said indentation forming said air gap at said indentation entirely separating the protruding portions and the centerpiece at the indentation.

3. The ballast transformer of claim 2 wherein there are two of said indentations disposed along opposite sides of said centerpiece and there are two protruding portions each attached to a side member each projecting part way into one of said indentations.

4. A ballast circuit including the ballast transformer of claim 3, further comprising a block of material in which said transformer is encapsulated and a temperature responsive means encapsulated in said block for disconnecting said primary coil from a power supply when the temperature rises above a predetermined level.

5. The ballast transformer of claim 1, wherein said transformer is an isolation transformer and said narrowed section of the centerpiece is disposed between said primary coil and the entire secondary coil.

6. The ballast transformer of claim 1, wherein said transformer is an autotransformer and said narrowed section of the centerpiece is disposed adjacent one end of said primary coil.

7. The ballast transformer according to claim 1, wherein said high-reluctance shunt includes a magnetic leg and an air gap intermediate and entirely separating the centerpiece and the side member near the narrowed section, and said magnetic circuit through the centerpiece and the side member being continuous throughout.

8. A ballast circuit including a transformer according to claim 1, output circuit means electrically connected with said secondary connection to at least one negative resistance characteristic gaseous discharge lamp, and means for connecting the primary coil of the transformer to a predetermined input voltage, the narrowed centerpiece section of the transformer core having a reduced cross-section narrowed to saturate when the input voltage is applied to the primary coil and the output circuit means begins conducting increasing current through a connected lamp.

9. An illuminating apparatus comprising first and second gaseous discharge lamps each having a negative resistance characteristic and a ballast circuit to which said lamps are connected for sequence starting and series operating wherein said ballast circuit comprises a transformer having a primary coil adapted to be connected to an alternating-current power supply, a secondary coil connected to supply current to said first and second lamps, and a magnetic core, said core being of the shell type having a centerpiece about which said primary and secondary coils are wound and a side structure connecting two opposite ends of said centerpiece, said centerpiece having a portion of reduced cross-sectional area formed by two indentations disposed on opposite sides of said centerpiece, saturable upon an increase in current in the secondary coil, and said side structure having two protruding portions

which project part way into said indentations to form high-reluctance shunts which are positioned to provide a path for a portion of the magnetic flux linking the windings of at least a part of said primary coil that does not link the windings of a substantial part of said secondary coil, the saturable portion of reduced cross-sectional area and the shunts comprising means for diverting an increasing proportion of the flux linking the primary coil away from the substantial part of the secondary whereby the tendency of the current flow in the secondary coil to increase as the resistance of the lamps decreases is diminished and whereby the voltage regulation of said ballast circuit is improved.

10. The apparatus of claim 9 in which the transformer core centerpiece and said structure form a continuous magnetic path linking both the entire primary coil and the entire secondary coil, the centerpiece, high
5 reluctance shunt, and outer structure forming a second magnetic path of higher reluctance than the continuous path and having air gaps where the protruding portions project part way into said indentations, the protruding portions being entirely spaced from and unconnected with the indentations where the protruding portions project.
